FILLER FOR GREASE GUNS

Glenn D. Brown, Waterloo, Iowa

Application March 27, 1939, Serial No. 264,353

2 Claims. (Cl. 221—47.5)

My invention pertains to fillers for grease guns, and one object thereof is to provide a device of this character with simple coacting means for compressively delivering a semi-solid lubricant 5 into a grease gun or other receptacle.

Another object is to combine with a manually controllable plunger a removable open top container for the lubricant and a reciprocatory piston therein fixed on the plunger means, the bottom 10 tom of the container having a delivery aperture with manually operable closing means therefor.

Another object is to supply associated bracketing devices for supporting said container and to adjustably support below the container a grease 15 gun or other receptacle to be supplied from the container and in adjustable relation thereto.

Another object of my invention is to furnish suitable side framing to mount said bracketed devices thereon whether fixedly or adjustably, 20 and shaped and constructed for rigidly connecting the framing to some fixed support in a desired relation thereto.

These and other objects related thereto are hereinafter fully described and claimed, and illustrated in the accompanying drawing.

It is however to be understood that various minor changes or improvements may be effected in the above structures, without departing from my invention and the scope of the claims.

The invention is particularly adapted for use 30 in filling stations or other places in supplying lubricant for filling grease guns, but may be removably positioned for transfer to other places or buildings, or to vehicles.

Fig. 1 is a side elevation of said device including a removable open top pail for grease or other semi-solid substances, the latter container adapted to receive and fit a movable piston seated therein above a bottom exit with controllable closure means therefor, and the container is shown in central vertical section, with part of the uppermost fixed arm broken away, and with the lowermost bracketing device indicated in lowered position in dotted lines. Fig. 2 is a top plan of the device, and Fig. 3 is a bottom plan of the container and its rockable closure for its delivery exit shown in open condition in dotted lines, and in full lines as opened.

Referring first to said Fig. 1, the numeral 1 denotes a vertically disposed hanger bar, preferably of wood or may be of other substance, and adapted to be fastened removably by nailing or otherwise to a supporting fixed structure within a building or otherwise. A tubular metal standard 2 is maintained in parallel relation to and spaced laterally from said hanger bar 1 connected by short arms 3 in pairs and fixed to the bar 1 by bolts 3a and to the standard 2 by soldering or otherwise rigidly. Upon the upper part 60 of said standard is a hollow bracket 4 having

bearing openings thereacross to seat rotatably a shaft 11 carrying at one end a crank 11a, and also carrying within the hollow of the bracket a pinion 12 meshed with a dentated rack 13 extending vertically therethrough, with an imperforate disk piston 14 fixed thereon.

On the standard 2 below the bracket 4 are a laterally spaced pair of divergent arms 5 having a disk 6 with a central perforation alined with a like perforation 17 in the bottom of a handled 10 open top pail 15, the pail containing a supply of grease or other lubricant 16, the pail being seated on the disk 6 with a rockable closure arm 18 (Fig. 3) pivoted at 19 at one end and having at its opposite end a down-turned fingerhold part 18a, the arm 18 having at one side edge a semi-circular clearance notch 18b. A fixed stud 20 on the bottom of the disk 6 spaced from the aperture at 17 restricts the scope of rocking of the arm 18 as shown in Fig. 3, and the stud is 15 laterally notched to seat therein when the arm is swung open to retain the arm in contact with the disk 6. Below the bracket arms 5 a similar bracket 7 with sleeve 8a and set-screw 8 is 20 adjustably mounted on the standard 2 and has 25 fixed thereon a disk 10, centrally apertured at 9 to seat thereon a grease gun hung therethrough removably. The crank handle 11a may be used to lower the rack 13 with its head 14 to compress the contents 16 of the pail 15, and when the 30 closure 18 is opened, to exude a supply of grease into the grease gun below as the apertured bracket 7 is suitably adjusted.

I claim:

1. In a device of the character described, supporting means, a container having an apertured bottom, an apertured plate mounted on the supporting means and supporting removably said container with their said apertures in alinement, a rockable valvular closure pivoted at its end on 40 the plate to cover said apertures, a stop on the plate for the closure when swung to uncover the apertures, and the stop having an edge recess to partially receive the closure when swung to uncover said apertures.

2. In a device of the character described, supporting means, a container having an apertured bottom, an apertured plate mounted on the supporting means and supporting removably said container with their said apertures in alinement, a rockable valvular closure pivoted at its end on 50 the plate to cover said apertures, a stop on the plate for the closure when swung to uncover the apertures, the opposite side of the closure being notched and to cross the apertures when swung 55 away from said stop, and a bracket mounted beneath said plate and adjustable on the supporting means, with an aperture therein alined with the aperture in said plate.

GLENN D. BROWN. 60
